UNITED STATES PATENT OFFICE.

CHARLES J. HODGE, OF HOGHTON, MICHIGAN.

DESIGN FOR A FRAME FOR SUPPORTING ORE OR MINERAL WASHING JIG-SCREENS.

SPECIFICATION forming part of Design No. 29,932, dated January 3, 1899.

Application filed December 12, 1898. Serial No. 699,072. Term of patent 7 years.

To all whom it may concern:

Be it known that I, CHARLES J. HODGE, a citizen of the United States, and a resident of Houghton, in the county of Houghton and

5 State of Michigan, have invented and produced a certain new and original Design or Useful Shape for a Frame for Supporting Ore or Mineral Washing Jig-Screens, of which the following, in connection with the accompanying drawings, is a full, clear, and exact specification.

In the said drawings, Figure 1 is a plan view of a frame of the character described embodying my design. Fig. 2 is an end view thereof, 5 partly in transverse section, on the line 2 2, Fig. 1; and Fig. 3 is a side view thereof, partly in longitudinal section, on the line 3 3, Fig. 1.

The leading features of my design consist 10 of the marginal frame portion A and the enclosed series of intermerged hexagonal webs B.

The frame A is oblong and rectangular and provided throughout at short intervals with 5 circular sockets a, surrounded by circular bosses a', and the hexagonal webs B, contiguous to the frame A, are merged therewith,

and the frame on its inner sides at all points excepting where the bosses a' are formed and where the webs B merge therewith are bevelled or rounded, as shown at a".

The webs B are very thin as compared with their depth and are coterminous in depth with the frame A, thus bringing their upper surfaces or edges, as well as their lower surfaces 35 or edges, respectively flush with or in the same plane as the upper and lower edges of the frame A. The webs B are also tapered from their lower to their upper edges, and their latter edges are rounded. At the junction between two of the hexagonal webs, at 40 one end of the frame, is formed a circular perforated boss C.

Having thus described my invention, what I claim as new therein, and desire to secure 45 by Letters Patent, is—

The design for a frame for supporting ore or mineral washing jig-screens substantially as herein shown and described.

CHAS. J. HODGE.
